UNITED STATES PATENT OFFICE.

EVERETT B. PRESTON, OF CHICAGO, ILLINOIS.

SHOE.

SPECIFICATION forming part of Letters Patent No. 234,723, dated November 23, 1880.

Application filed September 11, 1880. (No model.)

To all whom it may concern:

Be it known that I, EVERETT B. PRESTON, of Chicago, in the county of Cook and State of Illinois, have invented certain new and useful Improvements in Shoes; of which the following is a specification.

My invention relates to improvements in the construction of shoes, and the same is more particularly adapted to use upon what are usually known as "Arctic overshoes."

The object of this invention is to provide a means for putting on and off the shoe which shall render the aperture for the insertion of the foot readily and sufficiently expansible, and at the same time perfectly exclude the snow and water when the shoe is secured upon the foot; and the invention consists in providing the shoe with an opening centrally down the instep, which opening is filled with an expansible folding gore, folding upon the outside of the shoe, with a fold or wing at each side of the central opening, so that the folding gore lies symmetrically upon the instep, and, in conjunction therewith, a means of fastening the shoe, consisting of a strap passing from one quarter of the shoe to the other, outside of the folding gore.

In the accompanying drawings, which form part of this specification, Figure 1 is a perspective view of the shoe. Fig. 2 is a section from front to rear of the same, on the line of the fastening-strap. Fig. 3 is a top view of the shoe, showing the folding gore and upper part of the shoe expanded in position to admit the foot.

In said drawings, A is an opening or slit centrally down the instep, to permit the expansion of the shoe for the insertion of the foot. B is a gore, with two wings, b b, sym-

metrically folding down upon the instep. C 40 is the fastening-strap, secured to one quarter of the shoe, passing over the folding-gore to the buckle D, secured to the other quarter or side of the shoe.

It will be noticed that the opening for the 45 expansion of the shoe-top in my shoe is symmetrical down the central line of the instep, which renders a shoe having high quarters, such as Arctic overshoes usually have, more easily put on and off than when the opening 50 is down one or both sides. The expansible gore folds entirely upon the outside of the shoe, leaving the interior perfectly smooth, so that it feels more comfortable to the foot than when the gore or any part of it is folded 55 inferiorly. Moreover, I am thus enabled to use a single gore and obtain a symmetrical structure which will not interfere, in the case of male wearers, with the neat fit or set of the bottoms of the pantaloons; and my improved 60 shoe not only perfectly excludes the snow, but is also a very neat, strong, and durable construction of shoe.

What I claim, and desire to secure by Letters Patent, is—

The shoe having a central slit down the front of the instep, an expansible folding gore, constructed as shown, secured to the outside of the shoe at either side of said slit, and arranged to fold entirely outside the shoe, and 70 a fastening-strap extending from one quarter or side of the shoe to the other and over the, folded gore, substantially as set forth.

EVERETT B. PRESTON.
